EJECTOR FOR SLOT-CUTTING DIES

Jesse D. Klopfenstein, Chicago, Ill., assignor to
Colorgraphic Incorporated, a corporation of
Illinois

Application November 18, 1942, Serial No. 466,005

5 Claims. (Cl. 164—33)

In my prior application, Serial Number 458,046, I have disclosed a novel means for ejecting from the cutting dies the strips severed from a piece of cardboard in the operation of forming narrow slots therein. While such means are applicable to slots opening out through the edge of the piece of cardboard as well as to slots completely surrounded by cardboard material, the present invention has for its object simpler means for ejecting the strip from a slot that is in the nature of a deep, narrow notch in a marginal portion of the cardboard.

In carrying out my invention, I employ a sturdy spring as in the other form, but am able to dispense with a separate ejector bar by aligning the spring with the space between the rules for cutting the sides of the slot, and extending the spring into said space through the open end of the latter. It is immaterial how narrow the slot is, because the free end of the spring may be flattened without weakening the remainder to permit it to lie between rules spaced only a short distance apart. In this construction the parts are so proportioned that the end of the spring, while parallel to the upper edge of the rules between which it lies, normally projects somewhat above the same. Therefore, when a piece of cardboard is forced down to cut it, the free end of the wire also moves down and, as soon as the pressure is released, the wire again moves up and raises the little strip of cardboard out of the dies.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 is a plan view of a cardboard square from which has been cut a disk containing two long, narrow edge slots or notches; Fig. 2 is a plan view, on a larger scale, showing the die by means of which the disk was cut, the cardboard being shown in broken lines; Fig. 3 is a section on an enlarged scale on line 3—3 of Fig. 2; Fig. 4 is a section on line 4—4 of Fig. 2 and Fig. 5 is a section on line 5—5 of Fig. 2.

Referring to Fig. 1 of the drawing, A represents a piece of cardboard or the like from which a disk B has been severed, although it remains in the plane of the original sheet. Two deep notches or slots C and D extend into the disk from the periphery, the notch or open slot

5 being curved. The little tongues E and F, partially severed from the main sheet in the cutting of the slots or notches, still remain therein.

10 The die for cutting out the disk shown in Fig. 1, consists of a base 1, conveniently of wood, having set therein rules 2 that form a circle or ring divided at the places where the slots are to occur. At the point where the slot C is to be cut, there is a little gap in the ring and a pair of parallel rules 3, placed a short distance apart, extend inwardly through a distance equal to the length of the slot to be produced. Arranged across the inner ends of the rules 3 is a narrow rule 4. It will be seen that the rules 3 and 4 serve to cut out the tongue E of Fig. 1. At the point where the slot D is to occur there is another gap in the ring and here are located a pair of parallel curved rules 5 that meet cross rule 4; this group of three rules cutting out the tongue F of Fig. 1.

15 The ejector, in the arrangements shown, comprises a spring wire 6 of spring metal which may be larger in diameter than the distance between the rules 3, 3 or 5, 5, one end being deformed to have flat sides and a flat top and being thin enough to extend freely into the space between the corresponding rules. The other end of each of the spring wires is fashioned into an eye 8.

20 The parts are so proportioned that when the eye of one of the springs is placed on top of the base while the free flattened end extends between the cooperating slot-cutting rules, such free end projects somewhat upon the upper edge 25 of the rules as shown in Figs. 4 and 5; this being accomplished by properly curving the wire from a point adjacent to the eye to a point near the flattened free end. Each ejector is fastened to the base by a screw 9 extending down through the eye and into the base.

25 The parts are so proportioned that when the eye of one of the springs is placed on top of the base while the free flattened end extends between the cooperating slot-cutting rules, such free end projects somewhat upon the upper edge 30 of the rules as shown in Figs. 4 and 5; this being accomplished by properly curving the wire from a point adjacent to the eye to a point near the flattened free end. Each ejector is fastened to the base by a screw 9 extending down through the eye and into the base.

35 I have not described in detail the process of die cutting or the actual construction of dies, since these things are old and well known; the only novel feature being the strong, simple ejectors that prevent the clogging of the slot-cutting die portions by the cardboard material when pieces containing edge slots are cut from cardboard or the like in the usual way.

40 As heretofore pointed out, the spring wire may be made as heavy as desired, so as to be certain to eject the little tongues from the dies, no

45 matter how narrow the dies; due to the fact that only a short section at the free end of the

50 spring enters the space between the slot-cutting

55 rules. Consequently, although this free end sec-

tion of the wire may have to be quite thin, it may be deep enough in the vertical direction to enable it to withstand a sufficient downward pressure to bend a fairly heavy spring during a cutting operation. Also, the flattened end of the spring may be regarded as being a bar-like ejector element and the remainder of the spring as comprising a continuation of such element together with suitable spring means yieldingly to support the said element.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. The combination with a die for cutting a piece of cardboard or the like and forming a slot extending inwardly through one of the several edges, which comprises a base and rules rising therefrom and sharpened at their upper edges, including rules to make the cuts along the sides and the inner end of the slot: of a sturdy spring wire fastened at one end to the base at a point outwardly from the space between the slot-forming rules and so located that the free end of the wire extends into said space, and the wire being curved upwardly to cause its free end normally to project above the rules.

2. The combination with a die for cutting a piece of cardboard or the like and forming a slot extending inwardly through one of the severed edges, which comprises a base and rules rising therefrom and sharpened at their upper edges, including rules to make the cuts along the sides and the inner end of the slot: of a thick spring wire having one end flattened for entry into the space between the slot-forming rules, said wire being fastened at its other end to the base at a point remote from the slot forming rules and so located that the free flattened end lies between and parallel to the cutting edges of the rules that make the cuts to produce the side edges of the slot, and the spring curving upwardly from

the fixed end to the other end so that normally the free end projects above the cutting edges of the rules.

3. The combination with a die comprising a base and rules standing edgewise thereon and having sharpened upper edges, at least some of which rules are positioned to cut a slot opening out through an edge of a piece of cardboard or the like: of a sturdy spring wire having one end lying between and extending throughout the length of the slot-forming rules for making the cuts along the sides of the slot, said end of the spring normally projecting above the rules, and the spring curving downwardly from said end to the base at a point remote from the slot-forming rules and being there fastened to the base.

4. The combination with a die comprising a base and rules standing edgewise thereon and having sharpened upper edges, at least some of which rules are positioned to cut a slot opening out through an edge of a piece of cardboard or the like: of a sturdy spring wire having one end lying between and extending throughout the length of the slot-forming rules for making the cuts along the sides of the slot, said end of the spring normally projecting above the rules, and the spring curving downwardly from said end to the base at a point remote from the slot-forming rules and having there an eye lying flat on the base, and a fastening device extending through said eye and into the base.

5. The combination with a die for cutting a piece of cardboard or the like and forming a slot extending inwardly through one of the severed edges, which comprises a base and rules rising therefrom and sharpened at their upper edges, including rules to make the cuts along the sides and the inner end of the slot: of an ejector including a resilient means positioned outwardly from the outer ends of the rules adapted to cut the sides of a slot and a bar-like element projecting from said means into the upper part of the space between the slot-forming rules, parallel with the upper edges of the rules, for cutting the sides of the slot.

JESSE D. KLOPFENSTEIN.
